his Attorney.

UNITED STATES PATENT OFFICE.

JOHN J. POTTER, OF ST. LOUIS, MISSOURI.

LOOSE-LEAF BINDER.

1,184,014.

Specification of Letters Patent. Patented May 23, 1916.

Application filed August 21, 1915. Serial No. 40,687.

To all whom it may concern:

Be it known that I, JOHN J. POTTER, a citizen of the United States, and residing at St. Louis, in the State of Missouri, have invented a certain new and useful improvement in Loose-Leaf Binders, of which the following is a specification.

This invention relates to loose leaf binders of the type employed for holding sheets or leaves temporarily in book form. In this type of binders it is of extreme importance that the leaves may be freely turned to permit inspection, or the making of entries upon a determined leaf; that the leaves be held smoothly and evenly and perfectly flat, in order to facilitate the making of such entries; and that the leaves be susceptible of ready insertion or removal either individually or *en masse*.

20 This invention has for its objects to provide a highly simplified form of binder which effectually meets the above requirements and which may, at the same time, be manufactured and sold at an unusually low cost.

With these and other objects in view, the invention comprises the novel features of construction and combination of parts more fully hereinafter described.

25 In the accompanying drawings, Figure 1 is a perspective view of a loose leaf binder embodying the invention; Fig. 2 is an enlarged sectional view taken of the line 2--2 of Fig. 1 showing the arch in normal position; and, Fig. 3 is a similar view showing the arch in leaf-releasing position.

Referring to the drawings, it will be seen that the binder comprises the usual side boards 1 joined together by a flexible section 40 or back 2, said binder being adapted to receive and hold the sheets or leaves 3 temporarily in book form. These parts may, except as hereinafter explained, be of the usual or any other appropriate construction and 45 material.

Fixedly attached at their inner ends to one of the side boards 1, as a base, are a pair of binder posts 4 having sockets 5, and suitably spaced relatively to receive the leaves 3, 50 which are provided with the usual perforations 6 through the junction of which the leaves are adapted for engagement with said posts, there being provided in the base in rear of each of the posts 4, and singly positioned with respect thereto, a spring socket

7, preferably consisting of a snap fastener of the well known glove fastener type.

Cooperating with each of the posts 4 to hold the leaves 3, is a retaining member or arch 8 provided with a portion 9 adapted to enter and telescopically engage the socket 5, and having a leg 10 provided at its outer end with a head or button 11 adapted to snap into the spring socket 7 for detachably securing the arch to the base 1, as will be readily understood. It will be noted that, under this construction, and owing to the portion 9 engaging the post, the latter holds the arch firmly and securely in position, and relieves the connection 7-11 of undue strain, thus to prevent weakening of said connection.

In practice, supposing the parts 4 and 8 in the position shown in Fig. 2, the arch 8 may be grasped and pulled apically or outwardly, thereby causing the head 11 to snap out of the socket 7 and the portion 9 to escape from the post socket 5, thus wholly detaching the arch from the base and rendering the post 4 free to receive or discharge 80 the loose leaves, and, after insertion or removal of leaves as the case may be, a reversal of the above operation with respect to the arch causes the head 11 to snap into the fastener 7 to hold the arch in position on the base and for cooperation with the post 4.

It is to be particularly noted that, in the operation of the device, the leaves 3 may be readily turned backward over the arch 8 to permit of ready inspection of entries on, or the making of additional entries upon, one of the leaves, and that the latter will, as a result of the post standing perpendicular with respect to the base, lie perfectly flat and be held smoothly and evenly to facilitate the making of entries. Furthermore, as a result of the arch pieces 8 being readily detachable, as explained, thereby leaving the binder posts wholly free and unobstructed, the leaves may be quickly inserted or removed either singly or *en masse*.

Especial attention is directed to the fact that the parts of the device are, without affecting their efficiency, reduced to a minimum, and their construction and operation highly simplified, and that, in consequence, the binder may be made and sold at an unusually low cost. In attaining these ends, the invention is not necessarily restricted to the structural details herein shown and de-

scribed, and therefore, various minor changes may be made in such details without departing from the spirit or scope of the invention.

5 Having thus described the invention, what is claimed is:

1. A loose leaf binder comprising a base, a binder post carried thereby, an arch having a leg and adapted for coöperation with said post to hold the leaves, and means on the base for yieldingly engaging said leg to detachably hold the arch in position.
2. A loose leaf binder comprising a base, a binder post carried thereby, an arch having a leg and adapted for coöperation with said post to hold the leaves, and means flush with said base for yieldingly engaging said leg to detachably hold the arch in position.
3. A loose leaf binder comprising a base having a spring socket, a binder post carried by said base, and an arch adapted for coöperation with said post to hold the leaves,

said arch having a leg adapted for detachable engagement with said socket.

4. A loose leaf binder comprising a base, a post carried thereby, an arch telescoping with said post and coöperating therewith to hold the leaves, and means for yieldingly holding said arch in direct detachable engagement with said base.

5. A loose leaf binder comprising a base having a socket, an arch adapted to detachably engage said socket and having a leg, and a spring socket on said base adapted to detachably engage said leg.

6. A loose leaf binder comprising a base, an arch, a socket on said base adapted to receive one end of said arch and adapted to steady the same, and a spring socket on said base adapted to receive the other end of said arch.

In testimony whereof I affix my signature this 11th day of August, 1915.

JOHN J. POTT.
